SEWING MACHINE

Elliott R. Thompson, Wycombe, Pa.

Application December 16, 1932, Serial No. 647,571

8 Claims. (Cl. 112—11)

My invention relates to new and useful improvements in a sewing machine and more particularly to portable manually operated machines for sewing up the mouths of bags, especially after the same have been filled.

One of the features of the invention is that the machine may be supported by the hand of an operator and moved across the top of a bag to be closed whereby its cooperation with the bag will cause the machine to function.

An object of the invention is to provide a bag sewing machine which will be relatively light in weight, inexpensive in the cost of manufacture, whereby it may be used by small as well as large dealers, shippers or packers. The device is also comparatively small to permit its use without interference by a filled bag and should displace expensive and cumbersome equipment used in many plants at the present time.

Another object of the invention is to provide a machine of the class described of exceedingly simple construction having few moving parts so that the likelihood of wear upon the machine is reduced to a minimum and so that the machine will have practically nothing to get out of adjustment, but permitting the same to be easily and readily repaired or parts replaced when necessary.

The machine being portable as above outlined, its use increases the efficiency and flexibility of other manufacturing equipment and operations in any factory or packing establishment.

A further object of the invention is to provide a unique stitching mechanism.

A still further object of the invention is to provide means which will automatically sever the thread used in the sewing operations at the completion of such operations.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:—

Fig. 1 is a bottom plan view of a sewing machine constructed in accordance with my invention, with portions of the covers broken away to show the mechanism.

Fig. 2 is a section on the line 2—2 of Fig. 1, with the machine in its proper position.

Fig. 3 is an end view thereof looking toward

that end which carries the handle and the illustration showing the machine in its proper working position with a part of the covers broken away.

Fig. 4 is a section on the line 4—4 of Fig. 1.

Fig. 5 is a side elevation of the machine looking toward the right hand side of Fig. 1, but in an inverted position relative to Fig. 1.

Figs. 6, 7 and 8 are diagrammatic views showing several positions of the needle during the sewing operations.

In carrying out the invention as herein embodied, the numeral 10 represents the frame work generally which includes two plates 11 and 12 having adjacent edges spaced apart to provide a bag mouth receiving channel 13 which may be tapered at one end as indicated at 14, so as to form a wide entrance to the channel. The two plates are rigidly held in their relative positions by a forked and arched handle 15 including a horn 16 which is the grip, and if found desirable, said handle may include a bridge piece 17 extending across said plates or appurtenances thereof, and said handle is held in place by suitable fastening devices 18, such as screws, rivets or bolts and nuts. While not absolutely necessary, additional strengthening or bracing means 19 can be placed between the plates.

For specific description, the sewing mechanism will be considered as mounted on the undersides of the plates, with the needle and its driving parts carried by the plate on the operator's right hand side, although it will be understood that the mechanism can be mounted, the top faces of the plates and the positions of the several parts reversed when either on the bottom or top faces.

The plate 11 carries a wheel 20, generally known and hereinafter called an idler which for convenience of illustration is shown mounted upon an axle 21 depending from said plate 11. The idler 20 may be of any desirable size, but when mounted its periphery must travel across the channel 13 so that a bag in said channel can contact the idler. The circumference of the idler must be of suitable frictional material and is preferably a soft rubber tired wheel.

On the other plate 12 is mounted a similar wheel 22 which is the drive wheel and for convenience of illustration it is shown journaled upon an axle 23 fixed in the plate 12. The drive wheel 22 is of any desirable size, but is positioned so that its periphery travels across the channel 13 and when no sewing is being done, the circumferences of the drive wheel and idler should contact each other. Also like the idler, said drive wheel 22 has a suitable frictional material about

its periphery and should be compressible wherefore a soft rubber tired wheel is very good for this purpose.

Connected with the drive wheel 22 so as to revolve therewith is an element of a suitable motion transmitting mechanism, such as a sprocket wheel 24 having a chain 25 running over the same and over a driven sprocket 26 journaled upon another axle 27 carried by the plate 12, 10 which axle 27 is connected with a bevel gear 28 for revolving the latter. The bevel gear 28 meshes with a bevel pinion 29 which is mounted on an axle 30 supported in any suitable manner by the plate 12 as by a trestle bar 30' and said 15 axle is located in an oblique position relative to the axle 27 or said axle 30 is oblique to any imaginary perpendicular line having the plates as the base.

The pinion 29 revolves a crank 31 here shown 20 as a disc for the purpose of balance. If the axle 30 is revolvable then both the crank and the pinion are fixed to said axle, but if said axle 30 is stationary then the crank means and pinion are so connected that they will revolve together.

25 The idler and drive wheel are mounted in the same plane, and as above pointed out, they have a peripheral contact at a point between the two frame plates, therefore as the machine is passed over the mouth of a bag, said idler and drive 30 wheel will engage the same and be revolved. Upon revolving the drive wheel 22, motion will be transmitted to the crank means 31 from said drive wheel 22 through the sprocket 24, chain 25, sprocket 26, gear 28 and pinion 29, and said 35 parts are the preferred motivating means for the sewing mechanism.

The rubber rims of the idler and driving wheel have a number of specific purposes among which are: to clamp the material being sewn without 40 distorting the same; to impart a smooth driving action or motion to the sewing mechanism; and to facilitate the passage of the bag closer over the mouth of a bag without the likelihood of spreading or separating the frame members.

45 In actual practice the bevel pinion is at an angle at about forty-five degrees to the bevel gear and a line through the center of rotation of said pinion will intersect a line between the centers of the sprockets. This makes the plane 50 of the pinion, as the operator sees it, slope up and to the right at about forty-five degrees to a vertical line perpendicular to the plate 12.

A needle 32 of the latch type having a pointed end 33 with a hook 34 just to the rear thereof 55 of having a latch 35 coacting therewith to form an eye 36, has the end opposite the point connected with the crank means 31 by a universal joint 37 or other equivalent flexible connection and said needle is supported intermediate its 60 ends in an eyelet or needle guide 38 which becomes the fulcrum for said needle. Said eyelet, needle guide or fulcrum is supported by any suitable bracket 39 carried by the frame and more particularly by the plate 12. The location 65 of the fulcrum 38 is underneath the larger sprocket 24 adjacent the channel 13. Where the crank means 31 is actually a lever and even possibly with the disc arrangement, there should be a counterbalance means diametrically opposite the 70 universal joint 37.

In the path of travel of the needle and mounted on the edge of the plate 12 which forms one side of the channel 13 is a jaw 40 formed from a flat strip of metal having an offset rear end as 75 indicated at 41 and in this offset portion is formed

a notch 42. Also mounted in the path of travel of the needle and in cooperative relation to the jaw 40 and mounted on the edge of the plate 11 which forms the other side of the channel 13 is a movable jaw 43 having a free end terminating short of or in the region of the notch 42 in the first named or stationary jaw 40. Said movable jaw is also made from a strip of flat metal but this particular jaw must be resilient so that its free end will contact with the stationary jaw 40 for a purpose to be presently described, and said free end of the movable jaw 43 is also offset as at 44.

Both of the jaws 40 and 43 have apertures 45 therethrough for the passage of the needle and said apertures must be of a size that will permit of a circular movement which is substantially elliptical and in an inclined plane.

90 A spool, ball or other supply of thread may be mounted in any suitable place upon the machine or it may be hung on some outside support, such as a wall, or it may be allowed to rest upon the floor, but the thread strand from said supply passing through suitable devices to retard the travel of the thread and a portion thereof is held in 95 a straight line crosswise of the path of travel of the needle so as to be picked up by said needle, and for purposes of illustration, I have shown a thread tensioning device 46 which may be a spring wire 47 having an eye 48. The thread 100 therefore is run from the point of supply through the eye 48 thence through a guide 49 and through the aperture 45 in the movable jaw, and then between the offset ends of the two jaws.

At a suitable location between the fulcrum 110 point 38 and the jaws 40 and 43, is located a pin or post 50, its actual location is just short of the limit of the inward stroke of the needle point so that said needle point must pass around said post in approximately a semi-circle.

115 By reference to Figs. 6, 7 and 8, the operations of the needle in making the stitch will be obvious and in these views 51 represents the thread which runs from a source of supply through the thread guide 49, then through the 120 aperture 45 in the movable spring jaw 43, thence between the offset portions of both jaws where it is clamped, leaving a short free end hanging loose. Since the thread is under some tension 125 there is a straight section that lies in the path of travel of the point of the needle, between the thread guide 49 and the movable jaw, and said needle point may be curved slightly toward the latch side as in Fig. 8, and also slightly toward the front end of the machine when the needle 130 has pierced the article being stitched and the second mentioned curve is located at an angle to the other curve of about ninety degrees as in Fig. 6.

To stitch a bag, the operator holds the machine with the right hand and introduces one ear of a bag to be closed in the channel between the traction wheels 20 and 22 with the left hand. He then holds the machine still long enough to permit him to let go of the bag with his left hand 140 to use the same for straightening the mouth by tugging on the other ear. He then again grasps the ear which was introduced into the machine and holds it steady while he draws the machine toward himself over the bag with a slightly downward motion so that the machine will not run off the mouth of the bag. As the machine is drawn over the bag, motion will be transmitted to the needle as above outlined and the point of said needle will be projected through the parts of the 145

bag mouth which are held closely together by the jaws and backed up by one of them until the needle assumes the approximate position shown in Fig. 6. During this forward movement of the

5 needle through the bag, its latch will be opened permitting the hook to pick up the thread. As the needle is withdrawn from the bag carrying the thread with it, the latter will be closed to facilitate passage of the needle through the bag
10 in a reverse direction to prevent accidental displacement of the thread as shown in Fig. 7.

Thereafter the point of the needle will pass around the post 50 in order to hold back on the thread and permit the needle to pass through 15 the loop produced by twisting the thread due to the turning of the needle on its longitudinal axis. The further movement of the needle will cause the point thereof to be again projected through the bag mouth and these operations will continue 20 until the mouth of the bag is completely stitched from end to end.

By virtue of the method of mounting the needle and its passing through a definitely placed needle guide or fulcrum, it will be caused to oscillate 25 through the bag once every revolution of the bevel pinion. The universal joint allows it to vary its angle with the plane of the bevel pinion but causes it to make a complete revolution on its longitudinal axis during every revolution of the 30 bevel pinion and its passage through the bag. The needle guide is so located as to cause the pointed or sewing end of the needle to move through a generally circular orbit while piercing and withdrawing from the bag. This movement not only accomplishes the projection and 35 withdrawal of the needle, but also compensates for the travel of the machine over the bag. The needle guide, by being off the center line of rotation of the bevel pinion, produces the oscillatory 40 movement of the needle as the pinion rotates.

As the needle enters the fabric, the pinion and its associated crank means will be starting into the lower half of the travel of the needle and the open hook of the needle will be towards the front 45 end of the machine. The continued movement of the parts will cause the needle to rotate on its longitudinal axis so that the hook will turn upward to engage the thread. During the withdrawal movement of the needle, the hook will be turned 50 toward the rear end of the machine carrying a loop of thread with it. As the crank means turns through the upper half of its travel, the needle turns another one hundred and eighty degrees on its longitudinal axis so that when it again 55 enters the fabric the thread is looped around it and remains on the near side of the bag. Upon the next withdrawal of the needle with a new loop, the first loop is in contact with the back of the needle or that part opposite hook and latch permitting the new loop to be drawn 60 through the first one thereby forming a chain stitch with a single thread. The above operations will continue until the rear part of the bag being sewn passes beyond the path of travel of 65 the needle.

During the passage of the bag through the channel, the forward end of the bag mouth will engage a finger 52 which normally lies across the channel just beyond the free end of the movable jaw and said finger is carried by a knife 53 pivoted in any suitable manner as in a bracket 54 forming a part of the machine frame and said knife is normally held in a position across the channel and into the notch 42 in the stationary jaw 40 by means of a spring 55 having

one end anchored to the frame as at 56, while the end is connected to an arm 57 carried by the knife.

The engagement of the mouth of the bag with the finger 53 will move the latter to one side and therefore swing the knife out of the path of travel of the bag and against the action of the spring 55. After the bag is completely closed and the machine is passed over it, the spring causes the knife or cutter to snap back and sever the 85 thread between the bag and the point where said thread is clamped between the two jaws, and this backward movement of the knife is limited by the finger 52 striking against the stop 58, which for purposes of illustration, is shown as a part 90 of the bracket 39 and the latter is a part of the machine frame.

To insure smooth travel over the bag, a cover 95 59 is placed over the mechanism and in the instance shown depends from the frame with a slot 60 therethrough coincident with the channel 13. It will be obvious that said cover may be in two sections so that their adjacent edges will form the 100 passageway 60. The cover should be so connected with the machine frame that it can be readily removed whenever repairs or replacements are necessary.

By placing the drive on the top side of the frame or on the upper faces of the plates 11 and 12, the covering can be eliminated but in this 105 case it will be necessary to add guide wheels having traction treads to prevent the bag from becoming distorted by the pull of the operator as any distortion of the bag will cause a bending force on the needle. This can be done by making 110 the wheel on the thread side of the machine integral, concentric, and of the same diameter as the traction wheel on that side, while the companion traction wheel, the one on the needle side, should be of smaller diameter and should be 115 hung to run freely in an additional bracket on the present structure. This construction is necessary to avoid interference with the needle.

In practice, the largest practical gear reduction 120 between the driving wheels and the small bevel pinion does not allow as fine a stitch as is necessary in bagging some commodities. This condition can be overcome by using a small electric motor mounted on the machine frame so that power could be transferred to the gear train at 125 an intermediate point to be transmitted in two directions viz. to drive the needle and to propel the machine across the bag. Such a construction makes possible the more flexible use of gear ratios, and the machine may thus be designed to 130 make smaller stitches.

Of course I do not wish to be limited to the exact details of construction herein shown and described as these may be varied within the limits of the appended claims without departing from 135 the spirit of my invention.

Having thus fully described my invention, what I claim as new and useful is:—

1. A sewing machine comprising a frame having a channel for the reception of the object to be 140 stitched, a needle, and means to impart a plurality of simultaneous motions to the needle, said motions being reciprocatory, oscillatory, and rotary on its own longitudinal axis.

2. In a portable sewing machine, a frame having a channel therethrough for the reception of the article to be stitched, a needle, and means to cause the point of the needle to move across the channel in a generally circular orbit inclined relative to the path of travel of said article and at 145 150

the same time revolve the needle about its longitudinal axis.

3. The structure in claim 2, in combination with jaws located in the channel to guide the article through a portion of said channel and clamp the thread as the article passes beyond said jaws.

4. In a portable sewing machine, a pair of spaced plates in the same plane constituting a frame with a channel therethrough, means whereby the frame may be lifted by an operator and passed over an article to be stitched with parts of said article within the channel, said means also holding the plates in their spaced relation, a pair of traction wheels with rubber circumferences carried by the frame and having peripheral contact at a point in the channel, a driving sprocket wheel connected with one of said traction wheels and revolvable therewith, a driven sprocket wheel mounted on the frame with its center in line with the centers of the traction wheels, a chain running over said sprockets, a bevel gear connected with the driven sprocket wheel and revolvable therewith, a bevel pinion mounted in the frame with its axis oblique to the axis of the gear so that its center line of rotation intersects a line between the centers of the sprockets, a crank element carried by the pinion and revolving therewith in a parallel plane thereto, a stationary jaw secured to one of the plates and located in the channel and having an offset portion, a spring jaw having one end only secured to the other plate and coacting with the other jaw for guiding the article being stitched, the free end of said spring jaw having an offset terminus for contact with the offset portion of said stationary jaw to clamp a thread, both of said jaws having aligned apertures, a needle guide between the crank element and said jaws, a latch needle having one end attached to the crank element by a universal joint and fulcrumed in the needle guide whereby the point of said needle will move across the channel in a generally circular orbit inclined relative to the plane of the work and through the apertures in the jaws and also said needle will revolve on its longitudinal axis, a post located between the needle guide and said jaws about which the point of the needle

turns at its innermost position for looping a thread, means to guide the thread whereby a portion thereof will be held between said guide and the clamping parts of the jaws in the path of travel of the needle to be hooked thereby, and means for providing a tension on the thread.

5. The structure in claim 4, in combination with a pivoted thread cutter, means normally swinging said cutter into a notch in the stationary jaw forward of the thread clamping portions of the jaws, means connected with the cutter whereby it may be withdrawn from the notch by engagement with the article being stitched, and a stop to limit the movement of the cutter after being disengaged from said article.

6. A machine of the class described comprising a frame having a channel for the reception of the article to be operated upon, a needle, and means to cause a portion of the needle to bodily move in a conical path of travel and simultaneously reciprocate and rotate, said rotation being on its own longitudinal axis.

7. In a machine of the class described, a frame having a channel therethrough for the reception of the article to be stitched, a needle, means to cause the point of the needle to move across the channel in a generally circular orbit inclined relative to the path of travel of said article and at the same time revolve the needle upon its own longitudinal axis, jaws located in the channel to guide the article through a portion of said channel, said jaws having apertures therethrough for the passage of the needle and also functioning as guides for the thread, and a thread guiding means separate and distinct from said jaws.

8. In a machine of the class described, a frame having a channel for the reception of the article to be operated upon, a straight needle having a pointed end to penetrate the article to be operated on and further provided with a hook adjacent the pointed end to pick up a thread in forming a stitch, and means to cause the pointed end of the needle to move in a conical path of travel and simultaneously reciprocate and to rotate, said rotation being on the longitudinal axis of said needle.

ELLIOTT R. THOMPSON.
